F. H. CRUMP

LABEL HOLDER

Filed Jan. 26, 1926

Attorney

UNITED STATES PATENT OFFICE.

FRANK H. CRUMP, OF LOS ANGELES, CALIFORNIA.

LABEL HOLDER.

Application filed January 26, 1926. Serial No. 83,880.

My invention relates to loose leaf binders of the post type, and it has particular reference to devices for holding thereon labels by which the records held in the binder can be identified. Ordinarily the records contained in a loose leaf post binder are identified by pasting a paper or cloth label over the back edges of the leaves, and as so applied, the labels are unsightly and quickly worn off.

It is a purpose of my invention to provide a label holder of extremely simple and inexpensive construction which may be quickly and permanently secured to the back of a loose leaf post binder in such manner as to securely retain the label in display position, yet permitting the quick removal of the label when necessary, and also providing means by which the entire binder and its records may be easily and safely carried.

I will describe only one form of loose leaf binder and one form of label holder embodying my invention, and will then point out the novel features thereof in claims.

In the accompanying drawings,

Figure 1 is a view showing in perspective a loose leaf post binder having applied thereto one form of label holder embodying my invention;

Figure 2 is a view similar to Figure 1, showing the label holder employed as a carrying means for the binder;

Figures 3, 4 and 5 are views showing in horizontal section the binder and the several positions which the label occupies to apply the label holder to the binder;

Figure 6 is a detail perspective view of the label holder shown in the preceding views.

Similar reference characters refer to similar parts in each of the views.

Referring specifically to the drawings, my invention, in its present embodiment, is shown in Figure 6 as comprising a single sheet of metal or other suitable material, including a plate 15 of rectangular outline, with its longitudinal edges provided with co-extensive flanges 16 disposed at right angles to the plate. These flanges are constructed at one of their ends to form extensions 17 curved at their outer edges, as indicated at 17^a, and straight at their inner edges, as indicated at 17^b, while the adjacent end edge 16^a of the flange extends at an acute angle from the edge 17 so as to provide therewith a substantially V-shaped recess with a rounded crotch 17^c.

The flanges 16 are constructed at the opposite end to provide extensions 18 shorter than the extensions 17 and having a curved outer edge 18^a and a reversely curved inner edge 18^b, with the adjacent end edge 16^b of the flange co-operating therewith to form a substantially Y-shaped recess having a rounded crotch 18^c.

The flanges 16 adjacent the ends upon which the extensions B are formed are provided with openings in which are rotatably received the inwardly bent ends 19 of a yoke 20, the latter being formed of spring wire and, in its application to the flanges, sprung into place so that the ends 19 are permanently retained within the openings, yet serving to pivotally support the yoke so that it is free to swing to the several positions illustrated. This yoke 20 constitutes a handle by which the label holder when in applied position to a binder can be utilized to carry the entire binder from place to place.

In Figure 3, I have shown a label 21 consisting of a sheet of paper or other suitable material of the same width as the plate 15 but of greater length, so as to permit of the extended ends being bent inwardly to embrace the ends of the plate as indicated at 22. Other forms of label can be employed in connection with the holder, but the one here shown has been found to be ample for the purpose.

To illustrate the application of my invention, I have shown a loose leaf binder comprising an upper cover 23 and a lower cover 24 between which the leaves or records 25 are arranged and secured by a pair of posts 26 and 27. As shown in Figure 3, these posts are spaced apart and are disposed adjacent the back edge of the leaves 25.

To apply the label holder, the ends formed with the extensions 17 are inserted between the back edges of the leaves 25 and at a point between the posts 26 and 27, so that by longitudinally shifting the holder in the direction of the post 26, such post is finally moved into the crotches 17^c of the recesses, as clearly illustrated in Figure 4. It will be understood that to move the holder to this position it is necessary that the holder be rotated inwardly from the position shown in Figure 3 to that shown in Figure 4, and in the final position the plate 15 is disposed in parallelism to the back edges of the leaves 25, whereby the bent ends 22 of the label 21 are clamped between the plate and the

leaves, thus securely holding the label against accidental displacement from the holder. By now moving the holder longitudinally in the direction of the post 27, the 5 post will finally repose within the crotches 18^c of the corresponding recesses, as clearly shown in Figure 5. During this movement of the holder, the post 26 moves along the inner straight edges 17^b of the extensions 17, 10 and in the final position of the holder the extensions 17 still engage such post so that with the extensions 18 engaging the post 27 it will be manifest that the holder is 15 securely held against outward displacement from the leaves. Because of the curved edges 18^b of the extensions 18, it will be clear that when moving the holder to the position shown in Figure 5 these curved edges will function as cams to draw the holder inwardly of the leaves and thus firmly clamp the label in position.

With the holder applied as described, the handle or yoke 20 is disposed at the outer side of the leaves and free to swing to the 25 angular position shown in Figure 2, whence the handle may be gripped and the entire binder and its contents lifted and carried. Because of the mounting of the yoke 20, it will be manifest that when lifting the binder 30 the weight of the binder will operate to maintain the post 27 in engagement with the extensions 18, thus preventing the accidental displacement of the holder from the binder and permitting the free carrying of the 35 binder by means of the handle.

If, for any reason, it is desired to remove the label holder from the binder, it will be understood that by forcing the holder from the position shown in Figure 5 to that shown 40 in Figure 4 the extensions 18 will be moved out of engagement with the post 27, thereby permitting the holder to be swung to the position shown in Figure 3 and the subsequent removal of the holder from the leaves.

45 Although I have herein shown and described only one form of label holder embodying my invention, it is to be understood that various changes and modifications may be made therein without departing from the 50 spirit of the invention and the spirit and scope of the appended claims.

I claim as my invention:

55 1. A label holder comprising a plate having spaced flanges extending therefrom adapted to be inserted between the leaves of a two post binder, each of said flanges having terminal extensions arranged to provide recesses adjacent the extensions, the length of one of the extensions being greater than that 60 of the other, the spacing between the end of one of the extensions and the crotch of the recess at the other of the extensions being greater than the spacing between the posts of the binder, and the spacing between 65 the end of the other of the extensions and

the crotch of the recess at the first mentioned extensions being less than the spacing between the posts.

2. A label holder as embodied in claim 1, wherein the recess at the shorter extension 70 is inclined towards the plate from the inner to the outer end of the extension.

3. A label holder comprising a plate having spaced flanges extending therefrom adapted to be inserted between the leaves of a two post binder, each of said flanges having extensions projecting outwardly from its ends and arranged to provide recesses adjacent the extensions, one of the extensions being of greater length than the other, the spacing between the end of the longer extension and the crotch of the recess of the shorter extension being greater than the spacing between the posts of the binder, and the spacing between the end of the shorter extension and the crotch of the recess of the longer extension being less than the spacing between the posts:

4. A label holder comprising a plate having spaced flanges extending therefrom adapted for insertion between the leaves of a two post binder, said flanges having terminal extensions projecting outwardly from the ends of the flanges and arranged to provide recesses adjacent the extensions, the extensions on one end of the flanges being of greater length than those on the other end, the distance between the end of the longer extensions and the crotch of the recesses of the shorter extensions being greater than 100 the spacing between the posts of the binder, whereby upon insertion of the flanges between the leaves of the binder to engage one of its posts within the crotch of the recesses of the longer extensions, then pivoting the holder upon said post inwardly toward the binder and then shifting the holder longitudinally away from said post to engage the other post of the binder within the recesses of the shorter extensions, the longer extensions will remain in engagement with their respective post and will coact with the shorter extensions in securing the holder against lateral displacement from the binder.

45 5. A label holder as embodied in claim 4, 115 wherein the recesses of the shorter extensions are inclined with respect to the plate so that when the last mentioned post is seated in the crotch of the last mentioned recesses the holder will be secured against longitudinal displacement.

6. A label holder as embodied in claim 4 wherein the holder is provided with a handle so positioned that when grasped to lift the binder the weight of the binder will be 125 imposed on the last mentioned post to thereby maintain the binder in locking engagement with the posts.

7. A label holder comprising a plate having spaced flanges extending therefrom 130

adapted to be inserted between the leaves of a two-post binder, each of said flanges being recessed at its ends to provide oppositely projecting extensions, one of which is of greater length than the other with the overall length of the flange at a point between the crotch of the recess of the shorter extension and the end of the longer extension being greater than the spacing between posts of the binder so that upon insertion of the flanges between the leaves of the binder to engage one of its posts within the recesses of the longer extensions, then pivoting the holder upon said post inwardly towards the binder and then shifting the holder longitudinally away from said post to seat the other post within the crotches of the short extensions, the longer extensions will remain in engagement with their respective posts and will coact with the shorter extensions and the posts to secure the holder against lateral displacement from the binder.

8. A label holder as embodied in claim 1, wherein the longer extensions are provided with a long straight edge and a pointed end to facilitate initial insertion of the flanges between the leaves of the binder and the shorter extensions are provided with a cam edge adapted to be engaged with one of the posts of the binder for urging the holder inwardly of the binder.

9. A label holder having spaced flanges adapted to be inserted between the leaves of a two-post binder, said flanges having notches at at least two spaced points extending in the general direction of the length of the flanges with one of the notches being disposed in opposed relation to and of greater depth than the other of the notches, the spacing between the outer end of the notch of greater depth and the crotch of the notch of less depth being greater than the

distance between the posts of the binder, and the spacing between the outer end of the notch of less depth and the crotch of the notch of greater depth being less than the distance between the posts.

10. A label holder comprising a plate having spaced flanges adapted to be inserted between the leaves of a two-post binder, said flanges having their end portions provided with notches extending in the general direction of the length of the flanges with one of the notches being disposed in substantially opposed relation to and of greater depth than the other of the notches, the spacing between the outer end of the notch of greater depth and the crotch of the notch of less depth and between the outer end of the notch of less depth and the crotch of the notch of greater depth being so proportioned to the spacing between posts of a binder that upon inserting the end of the flanges having the notches of greater depth between the leaves to engage the crotch of the deeper notches with one of the posts, then swinging the holder inwardly towards the binder, and then shifting the holder longitudinally away from said post until the other post seats within the crotch of the notches of less depth, the first said posts will remain in engagement with the notches of greater depth, whereby the notches will coact with the posts to retain the holder against lateral displacement from the binder.

11. A label holder as embodied in claim 10, wherein at least one edge of the notches of less depth is inclined towards the plate from its crotch to its outer end so as to coact with the respective post when seated in the notch in retaining the holder against longitudinal movement away from the post.

FRANK H. CRUMP.
